UNITED STATES PATENT OFFICE.

FREDERICK KOCH, OF NEW YORK, N. Y.

DESIGN FOR A BADGE.

SPECIFICATION forming part of Design No. 34,608, dated June 4, 1901.

Application filed May 1, 1901. Serial No. 53,401. Term of patent 3½ years.

To all whom it may concern:

Be it known that I, FREDERICK KOCH, a citizen of the United States, and a resident of the city of New York, borough of Manhattan, 5 in the county and State of New York, have invented and produced a new and original Design for a Badge, of which the following is a specification, reference being had to the accompanying drawing, forming a part thereof, in which is represented a front elevation of a badge embodying the features of my design.

The leading feature of the design consists in two heart-shaped elements arranged one 15 below the other, their contracted portions facing in opposite directions.

The minor features of the design consist in the eyes at the top and bottom of the upper element, the eye at one side of the upper portion of the lower element, and the link which 20 connects the lower eye of the upper element with the eye of the lower element.

Having thus described my invention, I claim as new and desire to secure by Letters Patent—

The design for a badge herein shown and described.

In testimony whereof I have signed my name to this specification in the presence of two subscribing witnesses.

FREDERICK KOCH.
